UNITED STATES PATENT OFFICE.

VINCENZO CAMIZZI, OF NEW YORK, N. Y.

DESIGN FOR A TABLE.

SPECIFICATION forming part of Design No. 22,758, dated August 29, 1893.

Application filed June 23, 1893. Serial No. 478,665. Term of patent 3½ years.

To all whom it may concern:

Be it known that I, VINCENZO CAMIZZI, a subject of the King of Italy, and a resident of New York, county and State of New York, 5 have invented and produced a new and original Design for Tables, of which the following is a specification, reference being had to the accompanying drawings.

Figure 1. is a top or plan view of a table 10 showing my design. Fig. 2. is an end elevation.

The leading feature of my design consists in a top ornamentation comprising surface ornamentation representing a checker board 15 arranged within a circular border and a rectangular border adjacent the edge of the table top and having inwardly curved corners.

Referring by letter to the drawings, A designates the table top, and a designates checks 20 of a checker board of a contrasting shade with the top A. The checker board is arranged within two concentric rings a' , of surface ornamentation and a border a^2 , of a gen-

eral Grecian type, is arranged between the concentric rings a' . Two parallel lines of 25 surface ornamentation b , extend around the table top near its edge, and a fancy border b' , is arranged between these parallel lines b ; the corners are curved inward. The end pieces B, of the table have a scalloped lower 30 edge and have surface ornamentation, c . Legs C, have vertical stripes c' , extending from the end pieces B, to the feet C', which have stripes c^2 .

What I claim is—

The design for a table, substantially as 35 shown and described.

In testimony that I claim the foregoing as my invention I have signed my name, in presence of two witnesses, this 14th day of June, 40 1893.

VINCENZO CAMIZZI.
